WEATHER INDICATING INSTRUMENT

Joseph M. Gazzam III, 7801 Ruxway Road,
Baltimore, Md.

Filed Sept. 23, 1963, Ser. No. 76,688

Term of patent 14 years

(Cl. D52—7)

FIG. 1 is a perspective view of the weather indicating instrument looking upwardly and rearwardly from the front thereof;

FIG. 2 is a front elevation of the instrument;

FIG. 3 is a right end view of FIG. 2;

FIG. 4 is a bottom view of the instrument;

FIG. 5 is a top view of the instrument; and

FIG. 6 is a vertical sectional view along line 6—6 of FIG. 5.

The appearance of the undisclosed side is a mirror image of the side shown in FIG. 3.

I claim:

The ornamental design for a weather indicating instrument, as shown and described.
